UNITED STATES PATENT OFFICE.

JOHN C. PELTON, OF SIERRA MADRE, CALIFORNIA.

MOLD-FORMING APPARATUS.

1,409,464.

Specification of Letters Patent. Patented Mar. 14, 1922.

Application filed July 12, 1920. Serial No. 395,515.

To all whom it may concern:

Be it known that I, JOHN C. PELTON, a citizen of the United States, residing at Sierra Madre, in the county of Los Angeles and 5 State of California, have invented new and useful Improvements in Mold-Forming Apparatus, of which the following is a specification.

My invention relates to apparatus for 10 forming molds, especially adapted for the casting of concrete pipe or hollow tile of various configurations.

The object of my invention is to provide 15 an apparatus of the character above described, which may be quickly and accurately operated to project a pattern or a plurality of patterns into a suitable molding flask and to hold said pattern in proper relation therein while a proper molding material is 20 packed therearound, and then to withdraw the pattern, thereby forming a mold which may be filled with a suitable concrete mixture to produce a finished article.

Another object of my invention is to provide 25 means whereby the molded article may be efficiently ejected from the mold without materially destroying or effecting the molding material forming the same, whereby the same molding material and mold may be 30 used over again for the casting of subsequent articles.

Other objects will appear in the following description, will be pointed out in the claims and will be embodied in the accompanying drawings, in which:

Fig. 1 is a plan view of the apparatus embodying my invention, showing a plurality of patterns projected into a flask and the molding material packed therearound.

40 Fig. 2 is a vertical section of the same taken on the line 2—2 of Fig. 1.

Fig. 3 is a transverse plan section of the same taken on the line 3—3 of Fig. 2.

45 Fig. 4 is a section similar to Fig. 2, showing the pattern removed from the flask, and the concrete casting material poured into the molds formed thereby.

In carrying out my invention, 10 represents a tank formed of any suitable material 50 over the top of which is mounted a plate 11, which is provided with a plurality of circular perforations 12 of a diameter equal to the outside diameter of the pipes to be cast. A plurality of standards 13, which are centrally disposed with respect to the perforations 12, are secured to the bottom of

tank 10 and project upwardly in said tank and have mounted on their upper ends the circular disc members 14 which are disposed on a level with the plate 11 and are of a 60 diameter equal to the inside diameter of the pipes to be cast. By this construction it will be seen that ring like apertures 15 are formed between the walls of the perforations 12 and the peripheral edges of the disc members 14.

Mounted above the plate 11 is a flask 16, which is secured to said plate and the tank 10 by means of the angle irons 17, and mounted in the tank 10 is a hollow float member 18 adapted to slide on the standards 13 and to be guided thereby.

Mounted on the upper surface of the float 18 and secured thereto is a plurality of cylindrical patterns 19, of the size and shape of 75 the article to be cast which are adapted to project through the ring like apertures 15.

The tank 10 is made water tight and is provided with liquid inlet and outlet pipes 20 and 21 having cut-off valves 22 and 23.

In operating the apparatus, water or other liquid is admitted into the tank 10 through the pipe 20 which causes the float 18 to rise and project the pattern members 19 through the ring like apertures 15 up into the flask 85 16, as clearly shown in Fig. 2 of the drawings. The flask 16 is then filled with moist sand or other suitable molding material 24, which becomes packed around the pattern members. After the same has become sufficiently set the liquid is withdrawn from the tank 10 through the pipe 21, which allows the float 18 to descend by force of gravity and withdraw the patterns from the flask 16 as shown in Fig. 4, thus forming molds in 90 the sand into which the cement mixture 25 may be poured in the usual manner.

After the cement mixture has become sufficiently set the molding material may be pumped into an adjacent flask or otherwise 100 removed from the flask and the finished product taken from the flask; or liquid may again be admitted into the tank, thus causing the pattern member to rise and push the products upwardly and out of the mold, thus 105 preserving the mold for future castings.

It will be obvious that without departing from the spirit of my invention the mold may be formed permanently in the flask 16 of some solid material, such as wood or metal 110 and the pattern member used merely to eject the finished article from such mold.

What I claim is:

1. An apparatus of the class described, comprising a flask, a tank mounted below said flask, a float mounted in said tank, a pattern secured to said float, and means for lifting and lowering said float whereby said pattern may be projected into and out of said flask.
2. An apparatus of the class described, comprising a flask, a bottom for said flask provided with an aperture the walls of which being of a contour equivalent to the outer cross sectional shape of an article to be molded, a plate supported independently of said bottom disposed within said aperture of a contour equivalent to the internal cross sectional shape of said article, and a float means for projecting a pattern of the shape of said article through the space formed between the walls of the aperture in said bottom and the edges of said plate, into and out of said flask.
3. A molding apparatus, comprising a body member open at the top, a partition dividing said body member transversely into two compartments, the upper of said compartments forming a molding flask and the lower of said compartments forming a liquid chamber, a float member mounted in the liquid chamber and having a pattern disposed thereon adapted to be projected into the upper chamber, means to admit liquid to the lower of said compartments to cause the pattern formed on the float member to be projected into the molding compartment, and means to withdraw the liquid from said compartment to cause a withdrawal of the pattern from the molding compartment when the molding operation has been completed.

In witness that I claim the foregoing I have hereunto subscribed my name this 2nd day of July, 1920.

JOHN C. PELTON.
